Patented Oct. 29, 1918.

Albert M. Ward INVENTOR.

BY

Davis & Sumner
Esq. ATTORNEYS.

UNITED STATES PATENT OFFICE.

ALBERT M. WARD, OF ROCHESTER, NEW YORK.

SIGNAL.

1,283,002.

Specification of Letters Patent. Patented Oct. 29, 1918.

Application filed March 6, 1918. Serial No. 228,858.

To all whom it may concern:

Be it known that I, ALBERT M. WARD, a citizen of the United States, and a resident of Rochester, in the county of Monroe and State of New York, have invented certain new and useful Improvements in Signals, of which the following is a specification.

The present invention relates to signals and an object thereof is to provide in one structure a plurality of signaling elements, any one of which may be operated at will independently of the others.

To this and other ends, the invention consists of certain parts and combinations of parts, all of which will be hereinafter described, the novel features being pointed out in the appended claims.

In the drawings:—

Figure 1 is a view of a signal constructed in accordance with the present invention, the cover for the electromagnets and the armatures being removed;

Fig. 2 is a side view of the device shown in Fig. 1; and

Fig. 3 shows diagrammatically the circuits employed in connection with the signal.

At the present time, when a plurality of signaling elements, such as bells or buzzers, are operated from different points, each signaling element is mounted on a separate structure, thus requiring a separate electromagnet for each element as well as a separate base and other parts. According to this invention, all of the signaling elements are mounted upon a single base in compact form, and one electromagnet is employed for operating a plurality of the signaling elements.

Referring to the embodiment of the invention herein illustrated, 1 indicates the base, which, in this instance, supports an electromagnet, the axes of the coils 2^a and 2^b of which extends in parallel relation. The two coils are secured preferably to a common pole piece 3 by bolts 4 which act as cores, the opposite ends of the bolts being secured to two separate pole pieces 5 and 6 and said pole pieces being extended laterally to opposite sides of the coils. Arranged on opposite sides of the pair of coils are two armatures 7 and 8, these armatures being pivoted, respectively, at 9 and 10 to a flanged plate 11 which is secured on the under side of the

pole piece 3 by the bolts 4. Spring arms 12 and 13 may be provided, respectively, on the armatures 7 and 8, so that the upper or free ends of the armatures are held away from the pole pieces 5 and 6. Each armature 7 and 8 is also provided with a make-and-break device, and to this end carries a spring 14 contact finger 15 adapted to coöperate with an adjustable contact point 16, the latter being mounted on the base 1 and insulated therefrom at 17.

Also coöperating with the pole pieces 5 and 6 is an armature 18 pivoted above the pole pieces 5 and 6 at 19, and held away from the pole piece 5 by a spring arm 20 which is carried by the armature and bears against a fixed part 21. This armature 18 has its pivot arranged on a block 22 which carries the projection 21 and is insulated from the base 1. Coöperating with the armature 18 is a make-and-break device comprising, in this instance, a spring finger 23 coöperating with an adjustable contact 24 which is mounted upon a block 25 insulated from the base 1.

Means is provided whereby any one of the armatures may be vibrated without vibrating the other armatures. This means in this embodiment comprises three circuits employing a common battery 26, one pole of which is grounded at 27, while from the other pole the three circuits lead. The circuit which vibrates the armature 7 preferably embodies a push button 28 connected to the binding post 29 which, in turn, by a conductor 30, connects with the coil 2^a of the electromagnet. From the latter the circuit leads, by a conductor 30, to the adjustable contact 16 of the make-and-break device, and from the latter through the contact 15 and the armature 7 to the base 1, which is formed of metal and has the ground wire 31 connected to a binding post 32 thereon, said binding post 32 being in electrical connection with the base.

The circuit for effecting the vibration of the armature 8 embodies a push button 33 connected to the binding post 34 which, by a conductor 35, leads to the coil 2^b of the electromagnet. From this coil the circuit follows a conductor 36 leading to the adjustable contact 16 of the make-and-break device. From the adjustable contact 16 the

circuit leads through the spring contact 15, the armature 8, and the base plate 1 to the ground.

The circuit for effecting the vibration of the armature 18 embodies the push button 37 connected to the binding post 38 which, by a conductor 39, connects with the block or plate 22. After passing through the armature 18 and the make-and-break device 23, 24, the circuit follows a conductor 40 and the coil 2^a of the electromagnet, and leads to the conductor 30, thence to the armature 7 through the make-and-break device 15, 16, where it is grounded. This latter circuit, it will be noted, leads through two make-and-break devices, one for the armature 18 and the other for the armature 7. However, the make-and-break device of the armature 7 has a smaller frequency of action than the make-and-break device of the armature 18, and as a consequence the armature 18 vibrates so quickly that the make-and-break device 15, 16 of the armature 7 does not have time to operate, but instead forms a closed circuit. When the armature 7 is operated through the push button 28, the armature 18 is drawn toward the magnet 5, but as there is no current in this make-and-break device its action is practically *nil*.

Any suitable devices may be operated by the different armatures. It is preferred, however, to provide the two side armatures 7 and 8 with strikers 41 and 42, respectively, to operate upon two different bells 43 and 44 preferably of distinct tones. In this instance both bells 43 and 44 are supported upon a standard 45 to one side of the coils, the bell 43 being smaller than the bell 44 and being held in spaced relation to the bell 44 by a spacing device 46, the bell 43 being partially housed within the bell 44. So that the striker 42 may coöperate with its bell 44, such striker is deflected upwardly slightly, as shown in Fig. 2. The armature 18 in this instance acts as a buzzer, and does not have any striking element connected thereto.

From the foregoing it will be seen that there has been provided in one unitary structure three distinct signals which utilize between them only two coils. The arrangement of the armatures about the coils is novel, and provides a compact structure permitting the employment of two bells, one superposed over the other, together with a buzzer between the bell armatures. The circuit for energizing these coils is novel, but it will be understood that the invention is not limited to this circuit, and that the armatures may be operated in any other suitable manner.

What I claim as my invention and desire to secure by Letters Patent is:—

1. A signal comprising a base, a standard rising from said base, two bells supported

in spaced relation on said standard one above the other, two strikers one for each bell, and electromagnetic means on the base for operating either of said strikers.

2. A signal comprising a base, a standard rising from the base, two bells of different diameters mounted in spaced relation on the standard, the one of smaller diameter extending partially within the one of larger diameter, and two strikers operating on opposite sides of the bells, one coöoperating with the smaller bell and the other coöperating with the larger bell.

3. A signal comprising a base, a standard rising from the base, two bells of different diameters mounted in spaced relation on the standard, an electromagnet having coils arranged in parallel relation on the base and extending toward the bells, two armatures pivotally mounted on opposite sides of the electromagnet in proximity to the ends of the coils most remote from the bells, and strikers carried by the swinging ends of the armatures.

4. In a signal, two parallel and independently controllable coils having a common pole piece at one end and separate pole pieces at the other end, and two armatures, one pivoted in proximity to the common pole piece and having its free end adapted to coöperate with one of the separate pole pieces, and the other armature coöoperating with the two separate pole pieces.

5. In a signal, two parallel and independently controllable coils having a common pole piece at one end and separate pole pieces at the other end, the separate pole pieces being extended to the outer sides of the coils, and two armatures pivotally mounted in proximity to the common pole piece and having their free ends adapted to coöperate with the separate pole pieces.

6. In a signal, an electromagnet, two armatures coöoperating therewith, two make-and-break devices controlled by the armatures, one of said make-and-break devices being arranged in the circuit of the other make-and-break device and having a smaller frequency of action than such other device so that it does not operate when such other make-and-break device is operating.

7. In a signal, an electromagnet, two armatures coöoperating therewith, two make-and-break devices, and two circuits one of which includes the electromagnet, one armature and one make-and-break device, while the other includes the electromagnet, both armatures and both make-and-break devices, the make-and-break device which is included alone in the first circuit having a smaller frequency of action than the other make-and-break device, so that the first make-and-break device remains inactive during the action of the second make-and-break device.

8. In a signal, a single electromagnet hav-

ing two armatures, two make-and-break devices one of which has a smaller frequency of action than the other, and two circuits one of which includes the electromagnet and 5 both make-and-break devices and the other of which includes the electromagnet and only one of the make-and-break devices.

9. In a signal, an electromagnet having a

pair of coils arranged in parallel relation, two armatures arranged on opposite sides 10 of said pair, a third armature arranged at one end of the pair, and means for effecting the vibration of any one of the armatures without effecting the vibration of any other one of the armatures.

ALBERT M. WARD.
